UNITED STATES PATENT OFFICE.

ALVA H. BARNHILL, OF ALTOONA, KANSAS, ASSIGNOR OF ONE-FOURTH TO JAMES T. BARNHILL AND ARTHUR M. RICHARDSON, OF SAME PLACE, AND JOHN G. CERTAIN AND ROSE GALLAMORE, OF LA FONTAINE, KANSAS.

WASHING-MACHINE.

SPECIFICATION forming part of Letters Patent No. 599,213, dated February 15, 1898.

Application filed August 14, 1896. Serial No. 602,768. (No model.)

To all whom it may concern:

Be it known that I, ALVA H. BARNHILL, a citizen of the United States, residing at Altoona, in the county of Wilson and State of 5 Kansas, have invented certain new and useful Improvements in Washing-Machines; and I do hereby declare the following to be a full, clear, and exact description of the invention, such as will enable others skilled in the art to

10 which it appertains to make and use the same.

This invention relates to certain new and useful improvements in washing-machines; and it has for its object, among others, to provide a simple and cheap construction by 15 which clothes may be readily cleansed, requiring but little power, and by which injury to the clothes is prevented. It is made practically air-tight, and inside there are two rubbers, one of which has a corrugated bottom. 20 Simple means are provided for operation of the working parts, and provision is made for adjustment, where necessary.

Other objects and advantages of the invention will hereinafter appear, and the novel 25 features thereof will be particularly pointed out in the appended claim.

The invention is clearly illustrated in the accompanying drawings, which, with the letters of reference marked thereon, form a part 30 of this specification, and in which—

Figure 1 is an elevation of my improved washing-machine. Fig. 2 is a substantially central vertical longitudinal section. Fig. 3 is a vertical section on the line X X of Fig. 1. 35 Fig. 4 is a plan view.

Like letters of reference are employed to indicate like parts in the several views.

Referring now to the details of the drawings by letter, A designates the substantially 40 semicircular sides of the outer casing, and B the bottom, secured thereto in any suitable manner, and at their upper ends the sides are connected by the end piece C. The whole is supported upon suitable legs A' and may be 45 of any desired capacity. One of the sides is provided near its lower edge with a hole or opening a, closed by a stopper or other suitable means, and through which the water may be removed after the operation is completed.

50 The outer or lower semicylindrical rubber

comprises the substantially semicircular sides E, connected at their upper ends by the cross-bars e e', and the bottom is composed of the slats or rollers E', which may be of any desired shape in cross-section and mounted in 55 the sides E to revolve freely. This rubber is pivotally mounted within the outer case upon suitable pivots E², so as to rock freely.

F is the upper rubber, consisting of the semicircular sides, to which is connected the corrugated bottom f, of any suitable character and material. It is of such size as to fit within the inner or lower rubber and to rock therein, the two rubbers being mounted to be moved in opposite directions simultaneously. This 60 upper or inner rubber is pivotally mounted upon pivots G in the lugs or brackets G', which are secured to the inner faces of the side walls H of the top, which side pieces are connected at one end by the cross-plate h, and which is 65 hinged by suitable hinges h' to the top of the outer casing, as shown. Its other end has a depending portion H', which fits down in between the side walls of the outer casing and rests upon the cross-piece p thereof, so as to 70 close tightly and form practically an air-tight joint. The top is held in its closed position 75 by hooks I, engaging staples or analogous means i on the side walls of the casing, as shown. The ends and sides of this top may be 80 braced in any suitable manner and strengthened as by the metallic strips h², as shown. It may be provided with a suitable bail or handle I', by which it may be lifted when unlocked. 85

The rubbers are actuated as follows: To the cross-piece e' of the lower rubber is affixed a bracket or lugs J, in which is held a pin or pivot J', to which is pivotally connected the arm J², which extends upward, and to its upper end is connected pivotally, as at k, the bell-crank lever K, which at its elbow is pivotally mounted on the shaft L, arranged transversely of the machine and mounted in the brackets L', secured to the upper face of the 90 top. The other end of this lever is pivotally mounted, as at m, in the bifurcated end of the pitman M, the other end of which is connected with the crank-shaft N, mounted in the brackets N', rising from the top of the machine, and 95 100

this shaft is extended at one end and has secured thereto the wheel N^2 , having a crank-handle N^3 , by which it is operated.

O is a slide mounted to move in suitable guides O' on the top of the machine and having an opening o, through which passes the arm J^2 , the bottom plate of the guide having an elongated slot o' to permit of the operation of said arm J^2 . This slide covers the slot 10 through which the arm works and makes it practically air-tight. The lever M is slotted, as seen at P, the slot extending vertically and longitudinally, and in this slot works the slotted arm Q, a pin q, passing transversely 15 through the arm M, serving to limit the movement of the two parts with relation to each other. This slotted arm passes downward through an elongated hole r in the plate R, secured to the top of the machine, and through 20 the sliding plate R', which is mounted to reciprocate on top of the plate R. This arm Q extends through the opening in the top and is connected with the arms T, which are secured to the inner walls of the sides of the 25 inner and upper rubber, as shown.

The cover may have a hinged portion U, through which the clothes may be inserted when desired or which may provide for the inspection of the clothes within the machine, 30 and this may be held in its closed position in any suitable manner, as by the hasp U'.

The operation will be apparent. The turning of the wheel N^2 by its crank-handle causes actuation of the two rubbers simultaneously 35 in opposite directions. When it is desired to remove the clothes, the top is unlocked and, together with the entire actuating mechanism

and the inner rubber, is thrown back, when the clothes may be removed from the inner rubber. Any suitable means may be provided 40 for holding the top in its position and preventing its going too far. I have shown in this instance the plates W, which are provided with elongated slots w and pivotally connected at opposite ends to the outer sides of the 45 casing and of the top, as shown, so that the top may be moved on its hinges; but the top is limited in its movement by the engagement of the screws X, which ride in the slots, with the lower wall of the slot, as is clearly illustrated and as will be readily understood.

Modifications in detail may be resorted to without departing from the spirit of the invention or sacrificing any of its advantages.

What I claim as new is—

The combination with the two independent rubbers, the top, the crank-shaft, and its wheel and crank-handle, of the pitman connected with the crank of the crank-shaft, the bearing attached to said pitman and passing through 60 the slot into the vertical arm, the slotted arm connected with one of the rubbers and working through a slot in the pitman, a bell-crank lever connected with the other end of said pitman, and a rod connected with the bell-crank lever and with the other rubber, substantially as specified.

In testimony whereof I have signed this specification in the presence of two subscribing witnesses.

ALVA H. BARNHILL.
